UNITED STATES PATENT OFFICE

ADOLPH G. LOTTER, OF MILWAUKEE, WISCONSIN, ASSIGNOR TO H. C. MILLER COMPANY, OF MILWAUKEE, WISCONSIN, A CORPORATION OF WISCONSIN

LOOSE-LEAF BINDER

Application filed February 23, 1928. Serial No. 256,371.

This invention relates to certain new and useful improvements in loose leaf binders and refers more particularly to that type of binder especially adapted to preserving documentary records of public office, such as real estate conveyances, assignments, corporation articles, etc., as illustrated in Patent No. 1,056,926 issued to Henry C. Miller, March 25, 1918, and consisting of a back, cover members and substantially flexible but non-extensible binder posts pivotally and releasably connected with the ends of the covers. In this type of binder it has been customary to form the hinged connection between the back and the covers of leather, which has the disadvantage of drying out, often cracking and permitting the covers to become loose, and this invention has as its primary object to provide a loose leaf binder of the character described having a metallic hinge thus obviating the usual leather hinge and its attendant objectionable features.

A further object of this invention resides in the provision of a loose leaf binder having a back and cover members hinged thereto, the hinged connection consisting of metal plates secured to the cover members and having apertured members secured thereto which align with similar members extended from the edges of the back to receive a pivot rod.

And a still further object of this invention resides in the provision of a loose leaf binder of the character described having improved means for releasably connecting the post members with the covers.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far de-

vised for the practical application of the principles thereof, and in which:

Figure 1 is a side view of a loose leaf binder embodying my invention, a portion of the leaves being broken away to expose the flexible post member;

Figure 2 is a perspective view of the loose leaf binder in open position with the leaves omitted and parts thereof being broken away to more clearly illustrate structural details thereof;

Figure 3 is a fragmentary perspective view illustrating the binder in the act of being closed, and

Figure 4 is a fragmentary perspective view of a cover carried plate member to which are secured the apertured members forming a part of the hinge connection between the covers and back.

Referring now more particularly to the accompanying drawing, in which like numerals designate like parts throughout the several views, 5 designates the covers of a loose leaf binder which are hingedly connected to a back 6. A plate member 8 is secured to each cover member in any suitable manner adjacent its inner edge and has a portion extended therebeyond and folded on itself, as at 9, to provide a channel 10 extending across the length of the plate member, for the purpose later described.

Secured to the plate members at spaced intervals by spot welding or other means are hinge members 11 each formed of bendable metal medially offset to have one end engaging the folded portion 9 of the plate, as at 12, and curled, as at 13, to provide an aperture 14, the aperture 14 of the hinge members of each member 8 being approximately in line with the center of its channel 10. The members 11 cooperate with like members 15 extended from the edges of the back 6 to be positioned between the members 11 and receive a rod 16 to hingedly connect the covers with the back.

The folded inner edge of each portion 9 is cut away at three places, as at 17, to provide openings through which the adjacent ends of substantially flexible binder posts 18 extend to be pivotally and releasably connected

with the adjacent cover by members 19 slidably mounted within the channel 10. The members 19 have their inner edges cut away, as at 20, adjacent each opening 17 and have an extension 21 extended from one end of each 5 cutaway portion 20 to extend into an aperture in the adjacent post member as the member 19 is shifted longitudinally in the channel, one end of each member 19 being provided with an up-turned portion 22 to facilitate its movement in its channel.

The members 11 being stepped, and having an end extended over the folded portion 9 reinforces the same and prevents its spreading 15 from the plate 8.

As is described in the aforementioned Letters Patent, closing the covers forces the post members to assume a concave position, as illustrated in Figure 1, this being accomplished by struck out portions 23 which engage the post members as shown in Figure 3.

From the foregoing description taken in connection with the accompanying drawing, it will be readily apparent to those skilled in the art to which an invention of the character described appertains, that I have provided a loose leaf binder of the type described in which the fallacy of the usual leather hinge is entirely eliminated and in which an improved means for connecting the post members with the covers is provided.

What I claim as my invention is:

1. In a loose leaf binder of the character described, a back, covers, plate members carried by the covers, the inner ends of the plate members being folded upon themselves to provide a tubular portion, the inner edge of which is cut away at intervals to provide openings, substantially flexible binder posts having their ends provided with loops which extend into the tubular portion of the plate members through the openings, means positioned within the tubular portion of the plate members for releasably connecting the post members therewith, and means carried by the plate members for hingedly connecting the covers with the back.

2. In a loose leaf binder of the character described, a back, covers, plate members carried by the covers, substantially flexible binder posts, means releasably connecting the ends of the binder posts with the plate members at the inner edges of the plate members, and means hingedly connecting the plate members with the back at points spaced from the inner edges of the plate members whereby the pivotal connections of the binder posts with the plate members are positioned inwardly of the said hinged connections of the plate members with the back when the binder is closed.

3. In a loose leaf binder of the character described, a back, covers, plate members carried by the covers, the inner ends of the plate members being folded upon themselves to

provide a tubular portion, the inner edge of which is cut away at intervals to provide openings, substantially flexible binder posts having their ends provided with loops which extend into the tubular portion of the plate members through the openings, means positioned within the tubular portion of the plate members for releasably connecting the post members therewith, and means hingedly connecting the plate members with the back at points spaced from the inner edges of the plate members whereby the pivotal connections of the binder posts with the plate members are positioned inwardly of the said hinged connections of the plate members with the back when the binder is closed.

In testimony whereof I hereunto affix my signature.

ADOLPH G. LOTTER.
